BRACELET CLASP

Abbot A. Harman, New York, N. Y.

Application December 22, 1948, Serial No. 66,652

4 Claims. (Cl. 24—230)

1

This invention relates to clasps.

An object of this invention is to provide a clasp designed for use in a bracelet or other similar article, which will firmly lock the ends of the article together, and at the same time permit the ends to be readily disconnected.

Another object of this invention is to provide a clasp which can be used on a heavy bracelet, necklace or other article of jewelry, for firmly locking the article in applied position.

A further object of this invention is to provide a clasp which includes a double lock structure so that pressing of one part of the lock structure will not accidentally release the clasp.

A further object of this invention is to provide a clasp embodying means whereby the locking elements cannot be bent, strained or otherwise injured.

With the above and other objects in view, my invention consists in the arrangement, combination and details of construction disclosed in the drawing and specification, and then more particularly pointed out in the appended claims.

In the drawing,

Figure 1 is a detail end elevation of a clasp constructed according to an embodiment of this invention.

Figure 2 is a plan view of the device.

Figure 3 is a sectional view taken on the line 3—3 of Figure 2.

Figure 4 is a transverse sectional view similar to Figure 3 showing the clasp members in exploded position.

Referring to the drawing, the numerals 10 and 11 designate generally a pair of complementary bodies adapted to be secured by suitable fastening means as will be hereinafter described, to the ends of a flexible member such as a chain, bracelet or the like. As herein shown, the bodies 10 and 11 are of semi-circular configuration and the body 10 has fixed to the inner edge thereof a pair of cylindrical keepers or barrels 12 and 13.

The keepers or barrels 12 and 13 are mounted in a transversely arcuate groove or channel 14 which is formed in the body 10. The body 11 has fixed in a transversely arcuate groove 15 thereof a cylindrical barrel 16 forming a housing having a pair of spring-pressed locking bolts or pins 17. These bolts or pins 17 are of like construction and each is formed at its outer end with an angularly disposed bill 18 which when in extended and locking position is adapted to engage in an adjacent inner end of a keeper. The bolts or pins 17 are each provided with a longitudinally disposed keyway or channel 19 within which a key 55

2

20 is adapted to loosely engage. In practice the key 20 is pressed inwardly from the upper side of the barrel 16.

A spring 21 is disposed between the inner ends 5 of the bolts 17 and constantly urges the bolts 17 outwardly to locking position. As shown in Figure 3, the opposite ends of the barrel 16 are also inclined as indicated at 22 on substantially the same angle of inclination of the bills 18.

10 The keepers 12 and 13 have slidably disposed therein bolt releasing pins 23 and 24 respectively. The bolt 23 is provided with a channel or groove 25 within which a key 26 struck from the barrel 12 is adapted to loosely engage. The key 26 provides a means coacting with the channel 25 in limiting the outward movement of the releasing pin 23. The pin 24 is also formed with a lengthwise channel or groove 27 within which a key 28 struck from the barrel 13 is adapted to loosely engage. When the bolts 17 are in locking position these bolts will force the releasing pins 23 and 24 outwardly and the two clasp forming bodies 10 and 11 will be held against release when only one of the releasing pins is moved inwardly.

15 The clasp hereinbefore described is designed particularly for use on a relatively heavy bracelet, chain or the like, and will provide a secure and safety means for securing the ends of the bracelet or chain together. The barrels 12, 13 and 16 may be secured as by soldering or other fastening 20 means in the grooves of the bodies 10 and 11 or if desired may be formed integral with these bodies.

25 I do not mean to confine myself to the exact details of construction herein disclosed, but claim 30 all variations falling within the purview of the appended claims.

What I claim is:

35 1. A clasp comprising a pair of complementary parts, a centrally disposed barrel carried by one 40 of said parts having the ends thereof spaced inwardly from the adjacent margins of said one part, a pair of outer barrels carried by the other of said parts, said outer barrels being disposed in axial alignment with said central barrel when 45 said parts are disposed in face abutting relation, a pair of oppositely disposed locking bolts carried by said central barrel, a spring between said bolts constantly urging the latter outwardly to locking 50 position, and releasing pins slidably carried by said pair of barrels adapted to confront said bolts whereby inward movement of said releasing pins will move said bolts inwardly to released position.

2. A clasp comprising a pair of body members 55 adapted to be disposed when in locked position in

3

face abutting position, one of said members including a pair of aligned spaced apart keepers, the other of said members including a barrel engageable between the inner ends of said keepers, a pair of oppositely disposed bolts slidably carried by said barrel, a spring between said bolts constantly urging the latter outwardly to locking position, means limiting the outward movement of said bolts, and a pair of releasing pins slidably carried by said keepers adapted to confront said bolts for moving the latter inwardly of said barrel to released position.

3. A clasp for connection to the opposite ends of a chain or similar flexible article of jewelry, comprising a pair of body members, each member being formed with a transversely arcuate channel, a pair of cylindrical keepers fixed in the channel of one member and projecting laterally therefrom, a cylindrical bolt housing fixed in the channel of the other member and projecting laterally therefrom, said housing having oppositely inclined ends and engageable between the inner ends of said keepers, the inner faces of said members being disposed in substantially abutting relation when said bolt housing is disposed between said keepers, a pair of spring-pressed oppositely disposed bolts in said housing, means

4

holding said bolts against rotation in said housing, and bolt releasing pins slidably disposed in said keepers.

4. A clasp for connection to the opposite ends of a chain or similar article of jewelry, comprising a pair of body members adapted to be disposed in face abutting position when locked together, a pair of aligned spaced apart keepers on one of said body members, a barrel engageable between the inner ends of said keepers and carried by the other of said body members, a pair of oppositely disposed bolts slidably carried by said barrel, interengaging means on said barrel and said bolts limiting the outward movement of the latter, a spring between said bolts constantly urging the latter outwardly to locking position, a releasing pin slidably carried by each of said keepers adapted to confront said bolts for moving the latter inwardly of said barrel to released position, and interengaging means on each of said keepers and on the related releasing pins limiting the inward and outward movement of said releasing pins.

ABBOT A. HARMAN.
